STORAGE DRAWER FOR PRICING SYSTEM

Robert O. Smith, Seattle, Wash.

Application November 1, 1955, Serial No. 544,279

2 Claims. (Cl. 206—73)

The present invention relates to a novel device particularly designed for the convenient storage of printed cardboard or plastic strips commonly used in grocery stores to indicate the name or price of goods, but it is to be understood that the invention can be used as well for the storage of other strips, tags, or labels.

My invention aims to provide such a container which is of simple and economical construction and yet has means for gripping the strips in a manner permitting each to be easily individually removed from the container and readily replaced therein.

With yet additional objects and advantages in view which, with the foregoing, will appear and be understood in the course of the following description and claims, the invention consists in the novel construction and in the adaptation and combination of parts hereinafter described and claimed.

In the accompanying drawings:

Figure 1 is a top perspective view of my storage device with parts broken away.

Fig. 2 is an enlarged fragmentary vertical sectional view taken along line 2—2 of Fig. 1.

Fig. 3 is a fragmentary horizontal sectional view taken along line 3—3 of Fig. 2.

Referring to the drawings it is seen that an open-top rectangular container 10 having end walls 11 is subdivided by trays 13, 14 whose end walls are denoted 15, 16, respectively. The container and trays may be of conventional paper-covered cardboard construction and the former may be provided with a lid 19. End walls 15, 16 of the trays abut the inside faces of the container's end walls 11 and are desirably secured thereto as by staples 17.

Stretching along the longitudinal centerline of the strips it is desirable to leave more than one spring convolutions which would bear against one another if the spring were in a relaxed state. The end convolutions of these springs grip the end walls of the trays and those convolutions endwise of the trays are lodged and thus gripped between the end walls of the trays and the end walls 11 of the container. This gripping of the end convolutions discourages sidewise shifting of the springs, and furthermore, such shifting is positively limited by the staples 17. It will be noted that the springs are tensioned sufficiently

2

to separate the convolutions so that each strip 20 to be stored can be readily inserted between an adjoining pair of convolutions.

The depth of the trays is made substantially the same as the diameter of the springs and the depth of the container is determined by the maximum height of the strips to be stored. Perforce the trays may also be of varied widths depending upon the length of the strips.

In some instances for maximum ease of removal of the strips it is desirable to leave more than one spring convolution between adjoining strips so that the top edges of each strip can be most easily gripped. Increased spacing between strips is also desirable if multiple kinds of strips are in the same tray, since the increased spacing permits each to be read and thereby identified without first having to be removed.

The advantages of the invention, it is thought, will have been clearly understood from the foregoing detailed description. Minor changes will suggest themselves and may be resorted to without departing from the spirit of the invention, wherefore it is my intention that no limitations be implied and that the hereto annexed claims be given a scope fully commensurate with the broadest interpretation to which the employed language admits.

25 What I claim is:

1. In a storage device, a rectangular container, multiple rectangular trays mounted in the container and arranged side-by-side across the width of the container, said trays being shallower than the depth of the container and extending the full length of the latter, and a respective coil spring tensioned between the end walls of each tray to separate its convolutions and extending along the longitudinal centerline of the tray, said spring having a diameter approximately the depth of the tray and having end convolutions gripping the end walls of the tray and lodged between these end walls and the end walls of the container and means securing the end walls of the trays to the end walls of the container.

2. In a device for storing strips of a given maximum width and length, a rectangular container as high as the maximum width of the strips, multiple rectangular trays mounted in the container and arranged side-by-side across the width of the container, each of said trays being shallower than the container, as wide as the maximum width of the strips, and extending the full length of the container, and coil springs tensioned along the longitudinal center lines of the trays for receiving the strips between their convolutions, each of said springs having end convolutions gripping the end walls of the respective tray and lodged between these end walls and the end walls of the container, and means securing the end walls of the trays to the end walls of the container.
